ROLL-GRINDING MECHANISMS

Gunnar V. Hultgren, Milford, Conn., assignor to Farrel-Birmingham Company, Incorporated, Arsonia, Conn., a corporation of Connecticut

Application December 12, 1955, Serial No. 552,507

9 Claims. (Cl. 51—95)

This invention relates to roll-grinding machines and more particularly to a device for grinding the surface of rolls for various uses in calenders or other machines wherein a rotating grinding wheel is provided to rotate in contact with the surface of the roll to be ground, the roll also being rotated and relative movement effected between the roll and the grinding wheel in a direction longitudinally of the roll so that all points on the surface of the latter will be ground.

As illustrated, the roll to be ground is rotatably mounted upon a traveling carriage reciprocable in the direction of the axis of the roll while the grinding wheel is provided upon a movable wheel head or frame so that it may be moved toward and retracted from the work to feed it into the work at the beginning of a grinding operation and also to adjust the wheel as it wears. In addition, as is well known, many rolls are ground with a crown or concavity, and the roll-grinding mechanism of the present application provides for movement of the grinding wheel toward or from the work during longitudinal reciprocation of the roll so as to produce shapes of this character.

The feeding movement of the grinding wheel toward or from the work is usually accomplished by a feed screw operating in conjunction with a threaded nut carried by the wheel head and almost invariably the mechanism required for this purpose develops looseness or play resulting in backlash. For this reason movements of the hand wheel or other apparatus controlling the feed does not accurately reflect the motion of the wheel head particularly when changing from one direction to the other, thus changing the movement of the wheel head from a direction toward the work to one away from the work.

It is, of course, desirable to eliminate such backlash and this is effected by the present arrangement. As illustrated a coarse feed screw is employed to bring the grinding wheel into a position close to the work, and a fine adjustment or fine feed screw is employed to bring the grinding wheel against the work and then to feed it in gradually or to retract it gradually from the work. The wheel head is pivoted so that it may be tilted toward or from the work, and this fine feed screw acts upon a lever system to raise or lower the rear end of the wheel head and thereby tilt the wheel about its pivot so that it is either moved toward or retracted from the roll to be ground.

As the wheel head is normally urged in one direction by gravity, backlash is eliminated in that gravity acts to keep all parts of the adjusting mechanism in contact so that a small motion of the fine feed screw is reflected immediately in a corresponding motion of the grinding wheel regardless of the direction in which the latter is moved.

There is also incorporated in the device mechanism for effecting a crown or concavity upon the surface of the roll which comprises a crowning eccentric rotatably mounted on the base which carries the wheel head, the eccentric also acting upon the lever which in turn raises

2

or lowers the wheel head about its pivot. This greatly reduces the inaccuracies heretofore present in crowning or concaving the roll which are traceable to unavoidable inaccuracies in the bearings which support the crowning eccentric.

One object of the invention is to provide a new and improved roll-grinding mechanism.

A further object of the invention is to provide a roll-grinding mechanism having means for providing fine and accurate adjustments of the grinding wheel toward and from the roll with any lost motion or backlash between the parts eliminated so that any adjustment of the feed mechanism will be accurately imparted to the grinding wheel.

Still another object of the invention is to provide a roll-grinding machine having a grinding wheel rotatably mounted upon a wheel head which is pivoted on the frame and to provide an adjusting mechanism operable to move the wheel head about its pivot in such a manner that the wheel head will be moved in one direction by gravity and lost motion between the parts will be eliminated.

A still further object of the invention is to provide a grinding wheel of the character described wherein a lever is pivotally mounted upon the machine, which lever in turn acts against the pivoted wheel head to adjust the same in one direction and to provide a feed adjusting mechanism and also a crowning mechanism to actuate this lever to effect movement of the grinding wheel toward and from the work.

To these and other ends the invention consists in the novel features and combinations of parts to be hereinafter described and claimed.

In the accompanying drawings:

Fig. 1 is a top plan view of a roll-grinding mechanism embodying my invention;

Fig. 2 is a vertical sectional view on line 2—2 of Fig. 1;

Fig. 3 is a vertical sectional view on line 3—3 of Fig. 2;

Fig. 4 is a vertical sectional view on line 4—4 of Fig. 2;

Fig. 5 is a horizontal sectional view on line 5—5 of Fig. 2;

Fig. 6 is a detail view of a bracket supporting the lever mechanism which actuates the wheel head;

Fig. 7 is a detail view of the thrust member connected to the lever and engaging the wheel head;

Fig. 8 is a sectional view, showing the lever which actuates the wheel head in one position of its adjustment; and

Fig. 9 is a view similar to Fig. 8, showing the parts in another position.

To illustrate one embodiment of my invention, I have shown in the drawing a roll-grinding mechanism comprising a supporting base 10 having ways 11 and 12 thereon upon which is slidably mounted a carriage 13. Mounted upon the carriage are head and tail stocks 14 and 15 designed to carry the roll or workpiece to be ground, this roll being indicated in dotted lines at 16 in Fig. 2. Any suitable means may be employed to reciprocate the carriage 13 in a manner well known to those skilled in the art, and it will also be understood that during this reciprocation the roll or workpiece may be rotated by the motor 17 (Fig. 1).

Also adjacent the base 10 is a further base member 18 upon which the subbase 19 of the wheel head is slidably mounted for movement toward and from the workpiece or roll 16 (Fig. 2). The subbase 19 is, as shown in Fig. 4, mounted upon ways 20 provided upon the base 18.

Also carried by the base 18 is a housing 21 to which is secured an internally threaded nut 22 and, as shown in Fig. 2, a housing 23 is mounted upon the subbase 19 in which is rotatably mounted a screw 24 which is threadedly received in the nut 22.

From the above description it will be seen that the nut 22 is fixed relatively to the base 18, while the screw 24 is carried by the slidably mounted subbase 19 so that upon rotation of the screw 24 the subbase which, as will be hereinafter described, carries the wheel head and grinding wheel will be moved toward and from the workpiece. This effects coarse adjustment of the wheel head and grinding wheel.

The screw 24 is provided with a worm wheel 26 within the housing 23 and, as shown in Fig. 3, a worm 27 is rotatably mounted in the housing 23 to engage the teeth of this worm wheel and rotate the screw. The worm 27 may be rotated by either of the motors 28 and 29, the latter being designed to impart a relatively slow speed to the screw 24, while the motor 28 imparts a relatively rapid speed thereto.

Pivoted to the subbase at 31 is a wheel head 32 upon which is rotatably mounted at 33 the grinding wheel 34. As shown, this wheel head is pivoted at a point substantially below the axis 33 of the grinding wheel so that when the wheel head 32 is swung about its pivot, the wheel will be moved toward and from the work independently of the feeding of the subbase toward the work by the screw 24. As will be hereinafter explained, the fine adjustment of the grinding wheel toward and from the work and also the crowning and concaving adjustments of the grinding wheel are effected by this movement of the wheel head about its pivot.

Mounted upon the subbase 19 is a bracket 35, this bracket being shown more especially in Figs. 5 and 6, and comprises a base portion having upstanding therefrom two pairs of bearing plates designated at 37 and 38. A feed lever 39 (Fig. 5) is bifurcated at its rear end to provide spaced legs 40 and 41, these legs extending rearwardly so that one is pivoted between the plates 37, as shown at 42, while the other is pivoted to the other pair of plates 38 at 43. The forward end of this lever, as shown more particularly in Fig. 3, is provided with a roller 44 designed to rest by gravity upon a cylindrical nut 45 slidably mounted in a housing 46 carried by the subbase 19.

Rotatably mounted in a housing 47 which lies below the housing 46 and is carried by the subbase is the shaft 48 of a screw 49 threadedly received by the nut 45 so that upon rotation of the screw the nut 45 will be raised and lowered. It will be understood that the end of the feed lever 39 upon which the roll 44 is mounted will be raised when the nut 45 is raised and will be permitted to drop under the force of gravity when the nut 45 is lowered.

Also, as shown in Fig. 2, a bevel gear 50 is secured to the lower end of the shaft 48 which meshes with a bevel gear 51 slidably keyed, as shown at 52, to a shaft 53 rotatably carried in the base 10. The shaft 53 is rotated by means of a hand wheel 54 and belt 55 connecting the pulleys 56. It will be apparent, therefore, that when the hand wheel 54 is rotated and the nut 45 moved in a vertical direction, the feed lever 39 will be swung about its pivots 42 and 43 and, as explained herein-after, will result in the tilting of the wheel head about its pivot 31.

As shown more especially in Figs. 8 and 9, a keyway 57 is provided in the wall of the cylindrical nut 45 and a key 58 provided upon the housing 46 extends into this keyway to prevent the nut from turning when the screw 49 is rotated.

Rotatably mounted in the subbase 19 is a crowning shaft 60 (Fig. 2) upon which shaft is secured a worm wheel 61 with which is engaged a worm 62 (Fig. 4),

the worm 62 being carried by a shaft 63. The shaft 63 may be rotated through the bevel gears 64 and 65 from the gear 66 which may be connected with any suitable driving means such as the carriage 13 in order to be driven synchronously with the latter to effect the crowning or concaving of the work.

Secured to the outer end of the crowning shaft 60 (Fig. 2) is a crowning eccentric 68, the periphery of which is in engagement with a roller 69 mounted in a slide 70. This slide is mounted in ways 71 and 72 (Fig. 6) provided upon the bracket 35 and is held in position by the plate 73.

The upper surface of the slide 70 engages the lower surface of a roller 74 (Figs. 2, 5 and 8) carried by a crowning lever 75, which lever is pivoted at 76 to the feed lever 39.

Pivoted at 77 to the crowning lever 75 is an upwardly extending thrust member 78 having at its upper portion knife edges 79 which engage bearing blocks 80 in the wheel head 32 (Fig. 2) so that when the pivot point 77 on the crowning lever 75 is raised, the rear end of the wheel head will be raised, thus moving the grinding wheel toward the work, and the reverse action will also take place when the pivot point 77 is lowered due to the action of the force of gravity upon the wheel head which acts to maintain the bearing blocks 80 in engagement with the knife edges 79.

With this construction, it will be apparent that, as the lever 39 is pivoted at 43, when the free end of this lever, carrying the roller 44, is raised or lowered, the pivot point 76 of the crowning lever will be raised or lowered and, as movement of the other end of the crowning lever is resisted by the crowning eccentric 68, the lever 75 will be raised or lowered about the point of engagement of the roller 74 with the slide 70. This will serve to raise or lower the pivot point 77 of the crowning lever 75 which will in turn raise or lower the rear or right-hand end of the wheel head 32, as shown in Fig. 2, so as to swing the wheel head about its pivot 31 and thus move the wheel toward or from the work. Also due to the action of the crowning eccentric 68, the roller 74 carried by the crowning lever 75 will be moved upwardly or allowed to move downwardly by the movement of the slide 70, thus moving the crowning lever 75 about its pivot 76 (as at this time the feed lever 39 is at rest), thus also effecting movement of the wheel head about its pivot with the same result as before.

A flexible shaft 81 may be secured to the screw 49, which flexible shaft leads to an indicating dial 82 which will indicate the position of the grinding wheel 34 as adjusted by the fine adjustment mechanism.

As shown in Fig. 5, the wheel head 32 is guided in its vertical movements by guide blocks 83 secured to the wheel head by bolts 84 which bear against portions 85 of the bracket 35.

In operation, after a roll to be ground has been mounted upon the carriage 13, the subbase 19 will be fed toward the work by rotation of the screw 24 by the appropriate motor 28 or 29. This movement of the subbase toward and from the work is, of course, necessary to set up the machine for rolls of different diameter.

Thereafter, to effect fine adjustment of the grinding wheel 34 with respect to the roll 16, the hand wheel 54 is rotated which serves as explained to rotate the shaft 48 and screw 49, effecting elevation of the nut 45. This will operate to raise the roller 44 and the free end of the feed lever 39 about its pivot point 42. This in turn raises the pivot point 76 of the crowning lever 75 which, through the member 78, effects vertical movement of the free end of the wheel head 32 about its pivot 31 to feed the wheel toward the work.

If the nut 45 is lowered by reverse rotation of the hand wheel 54, gravity acting upon the wheel head 32 and lever 39 will maintain the roller 44 in engagement

with the nut 45 as it is lowered, and the wheel head will be moved in a clockwise direction about its pivot 31, thus withdrawing the grinding wheel from the work. There will be no backlash or play when the movement is reversed due to the fact that the roller 44 will always be maintained in contact with the nut 45 by gravity.

In a similar manner rotation of the crowning eccentric 68 will effect movement of the wheel head. Due to the eccentricity of this wheel, the slide 70 will be raised and lowered, effecting corresponding movements of the roller 74 attached to the crowning lever 75. Raising of the right-hand end of the crowning lever 75, as shown in Figs. 2, 8 and 9, will move this lever about its pivot 76, thus raising the free end of the wheel head 32. When the slide 70 is permitted to drop, gravity will maintain the roller 74 in contact with the slide and the free end of the wheel head will be permitted to drop as gravity will maintain the bearing blocks 80 in engagement with the knife edges 79. Again gravity will maintain the parts in contact during the reverse movement thereof so that there will be no backlash or play which will result in more accurate crowning or concaving of the work as previously described.

It will be seen that the feed motion of the grinding wheel may be more accurately measured than in prior constructions in that the movement of the adjusting nut 45 will be accurately read upon the dial 82, and as the roller 44 is always in contact with the nut, this reading will be accurate. Any play or lost motion in the connections between the hand wheel 54 and the feed screw will not affect the reading of the dial which will accurately reflect movement of the adjusting nut. Moreover, the feed motion will be measured immediately and directly regardless of the direction in which the wheel moves, and there will be no backlash which will affect this reading.

In addition the fine feed motion of the grinding wheel toward and from the work is attained by a pivotal movement of the wheel head rather than by a sliding movement as has been the conventional arrangement.

It will also be apparent that the movement of the grinding wheel either by the fine feed adjustment or by the crowning eccentric 68 is effected by a series of levers, these levers and their connection with the wheel head being so arranged that the movement of the free ends of the levers is considerably greater than the movement imparted to the adjacent portion of the wheel head. Therefore, any mechanical errors which might occur in the manufacture of the parts would only appear in a greatly reduced degree in the movement of the grinding wheel, such errors being reduced to the point where they will no longer be significant in the product being ground.

It will also be understood that while the improvements are shown as applied to a roll-grinding machine, they may be employed in all types of grinding machines, for example, in those for grinding small or large mechanical parts.

While I have shown and described a preferred embodiment of my invention, it will be understood that it is not to be limited to all of the details shown, but is capable of modification and variation within the spirit of the invention and within the scope of the claims.

What I claim is:

1. A grinding machine comprising a work-supporting means, a base for supporting a grinding wheel adjacent said means, a subbase mounted on said base for sliding movement toward and from the work, a wheel head and a grinding wheel rotatably mounted thereon, said wheel head being pivoted on the subbase adjacent the wheel, coarse adjustment mechanism for moving the subbase toward and from the work-supporting means, fine adjustment mechanism for swinging the wheel head about its pivot for fine adjustment of the wheel relatively to the work, said fine adjustment mechanism comprising a screw-operated member carried by the subbase, means for actuating said screw-operated member, a lever pivoted on the

subbase adjacent one end and having a part remote from its pivot resting on said screw-operated member, a thrust member imparting movement from said lever to the wheel head, and a rotatable crowning cam member mounted on the frame and operatively connected to said thrust member to actuate the same.

2. A grinding wheel mechanism as in claim 1 wherein the thrust member for imparting movement from the lever to the wheel head is connected to said lever at a point between its pivot and the part resting on said screw-operated member whereby said thrust member is moved through a lesser distance than said screw-operated member.

3. A grinding mechanism comprising work-supporting means, a base for supporting a grinding wheel adjacent said means, a subbase mounted on said base for sliding movement toward and from the work, a wheel head pivoted on said subbase and a grinding wheel rotatably supported on said wheel head, said pivot point being adjacent but below said wheel axis, coarse adjustment means for moving said subbase toward and from the work support, fine adjustment mechanism carried by said subbase for swinging the wheel head about its pivot for fine adjustment of the wheel relatively to the work, an eccentric crowning cam carried by the subbase for swinging said wheel head about its pivot for effecting contouring of the work, lever means for transmitting motion from said fine adjustment mechanism and said crowning cam to said wheel head, said lever means comprising a lever pivoted on the subbase and having a member remote from its pivot engaging the fine adjustment mechanism, and a pivotally mounted thrust member moved by said lever and engaging said wheel head.

4. A grinding mechanism comprising work-supporting means, a base for supporting a grinding wheel adjacent said means, a subbase mounted on said base for sliding movement toward and from the work, a wheel head pivoted on said subbase and a grinding wheel rotatably supported on said wheel head, said pivot point being adjacent but below said wheel axis, coarse adjustment means for moving said subbase toward and from the work support, fine adjustment mechanism carried by said subbase for swinging the wheel head about its pivot for fine adjustment of the wheel relatively to the work, an eccentric crowning cam carried by the subbase for swinging said wheel head about its pivot for effecting contouring of the work, said fine adjustment mechanism comprising a vertically movable screw-operated element, lever means for transmitting motion from said fine adjustment mechanism and said crowning cam to said wheel head, and said lever means comprising a lever pivoted on the subbase and having a follower remote from its pivot engaged by said screw-operated element, a second lever pivoted on an intermediate portion of said first lever and actuated from said crowning cam, and a thrust member carried by said second lever and engaging said wheel head.

5. A grinding mechanism comprising work-supporting means, a base member having a wheel head pivotally mounted thereon, a grinding wheel rotatably carried by said wheel head, a lever connected to said wheel head to move the latter about its pivot, a plurality of means to actuate said lever, one of said means comprising a rotatably mounted cam member, and the other of said means comprising a second lever pivoted on the base member to which second lever said first lever is pivoted and fine adjustment means to actuate said second lever.

6. A grinding mechanism comprising work-supporting means, a base member having a wheel head pivotally mounted thereon, a grinding wheel rotatably carried by said wheel head, a lever connected to said wheel head to move the latter about its pivot, a plurality of means to actuate said lever, one of said means comprising a rotatably mounted cam member, and the other of said means comprising a second lever pivoted to the base member and having the first lever pivoted thereto and a screw-operated

vertically movable member carried by said base member and operatively engaging said second lever to actuate the same.

7. A grinding mechanism comprising a work-supporting means, a base for supporting a grinding wheel adjacent said means, a subbase mounted on said base for sliding movement toward and from the work, a wheel head pivoted on the subbase and a grinding wheel rotatably supported on said wheel head, said pivot point being adjacent but below said wheel axis, coarse adjustment means for moving said subbase toward and from the work support, fine adjustment mechanism carried by said subbase for swinging the wheel about its pivot for fine adjustment of the wheel relatively to the work, an eccentric crowning cam carried by the subbase for swinging said wheel head about its pivot for effecting contouring of the work, lever means for transmitting motion from said fine adjustment mechanism and said crowning cam to said wheel head, said lever means comprising a lever pivoted on the subbase and having a follower remote from its pivot engaging said fine adjustment mechanism, a second lever pivoted on an intermediate portion of said first lever and actuated from said crowning cam, and a thrust member carried by said lever and engaging said wheel head.

8. A roll-grinding mechanism comprising work-supporting means, a base member having a wheel head pivotally mounted thereon adjacent the work-supporting means, a grinding wheel carried by the wheel head, a lever pivotally mounted on the base member below the wheel head, a

second lever pivoted to an intermediate portion of the first lever and having an upwardly projecting thrust member to engage and move the wheel head about its pivot, and crowning mechanism to engage and move said second lever about its pivot with the first lever.

9. A roll-grinding mechanism comprising work-supporting means, a base member having a wheel head pivotally mounted thereon adjacent the work-supporting means, a grinding wheel carried by the wheel head, a lever pivotally mounted on the base member below the wheel head, a second lever pivoted to an intermediate portion of the first lever and having an upwardly projecting thrust member, said thrust member having a knife edge at its upper end engaging the wheel head from below to move the latter about its pivot, and crowning mechanism to engage and move said second lever about its pivot with the first lever.
